PAPER BOX

Harold S. Fuller, Winchester, Mass.

Application January 2, 1935, Serial No. 51

4 Claims. (Cl. 229—16)

The present invention relates to improvements in receptacles for enclosing hats and similar articles, and is more particularly concerned with a paper box which may be readily constructed from flat pre-cut sheets of cardboard or the like and glued in assembled relationship.

The purpose of the invention is to provide an attractive and economical box for the reception of hats and similar fragile articles, which offers numerous advantages over any type of box for similar purposes at present available. To this end a feature of the invention contemplates the provision of a paper box having top and bottom portions which are permanently connected with a side wall and not removed therefrom, and with an opening in the side wall approximating generally the width of the box to permit the removal of any article therein, this side opening being closed by a flap which is hinged to the side wall to swing in a plane generally parallel to the top and bottom, and which in closed position contacts the margins of the top and bottom and closely conforms to the contour of the permanent side wall. The flap may be retained in closed position either by connection between the free end and the side wall, or by overlapping tongues projecting from the top and bottom which are connected by a cord or the like passing outside of the flap when the latter is closed.

In a simple and attractive embodiment of the invention the top and bottom portions are hexagonal in outline, and are permanently closed about four of the six sides. The remaining two sides provide an opening through which access is had to the interior of the box, and are detachably closed by a flap hinged at one end of the opening and engaged at its opposite free end with the opening. The flap presents two flat faces and when in closed position closely contacts with the margins of the top and bottom. It is retained in position by tongues projecting from the top and bottom which project both within and without the flap to hold it in closed relationship. The flap may be readily opened to expose the entire interior of the box without requiring the removal of the box from a pile of boxes in which it may be located.

In the accompanying drawing illustrating the preferred form of the invention, Fig. 1 represents a perspective of the box with the flap in closed position; and Fig. 2 is a similar view of the box with the flap opened to expose the interior.

The box shown in the illustrated embodiment of the invention comprises a hexagonal top portion 10 and a similarly shaped bottom portion

12. These two portions are permanently connected and closed about four sides by a side wall 14, connected with the top and bottom portions by flanges 16 and 18, respectively, which are turned up and glued to the side walls. Hinged 5 at one end of the side wall is a flap 20 which is actually an integral extension of the side wall, and which is provided with two flat faces 22 and 24 corresponding to the flat faces of the side wall. This flap is designed to completely close 10 the opening remaining in the side wall, and has a free end 26 projecting within the side wall when closed, and a locking tab 28 which may extend without the side wall to hold the flap in position within, as desired.

15 The flap is maintained in close contact with the margin of the top and bottom through tongues 30 which are designed to extend within the flap when closed, and locking tongues 32 which extend without the flap and are retained 20 by a flexible tie 34.

Obviously the provision of a multiple-sided box of this character has many advantages, as it permits the use of a side opening and a closure flap which is hinged at the juncture of the flat sides 25 and thus is not readily distinguished. Furthermore, by the provision of more than four sides to the box, the closure flap departs from a straight side and is better able to conform closely to the top and bottom, and in addition may be 30 locked in satisfactorily closed position by relatively short retaining tongues or the like. Furthermore, the box in transit can be carried by the flexible tie, and due to the permanent closure of the top and bottom which then become the 35 sides, there is no liability of dislodgement and accidental opening of the receptacle as would be the case with a removable cover. When employed for enclosing articles on a shelf, a pile of 40 boxes may be stacked and individual articles removed therefrom without the necessity of removing the enclosing box from the pile in which it is located.

45 What is claimed is:—

1. A paper box for the reception of hats and 45 the like comprising top and bottom portions having more than four straight edges at the margin, flat side portions permanently connected to the top and bottom portions, an opening extending throughout at least two of the flat sides, a closure 50 flap hinged at one side of the opening to a flat side portion and having a free end engaging with the side portion at the opposite side of the opening, the closure having two or more flat portions 55 to contact the margin of the top and bottom

and conforming to the shape of the permanent side wall when in closed position, and means for retaining the closure in this position.

- 5 2. A paper box for the reception of hats and the like having hexagonal top and bottom portions, a side wall permanently connected therewith to present four flat faces, an opening occupying the equivalent of two flat spaces, a closure flap hinged to the side wall at one end of the opening comprising two flat faces and with a free end adapted to engage with the flat side at the opposite end of the opening, and means upon the top and bottom portions to engage and hold the closure flap in close contact therewith.
- 10 15 3. A paper box for the reception of hats and the like comprising top and bottom portions of like contour each having five or more straight sides, a continuous side wall enclosing the space between the top and bottom portions and permanently connected to a majority of the straight sides by connector flaps, the side wall being unconnected to at least two of the straight sides to provide an opening to the interior, a closure flap projecting from the end of the side wall

and conforming thereto, the closure flap conforming in shape and dimensions to two of the straight side edges when assembled in closed relation to present the appearance of a continuous side wall, and means for connecting the 5 free end of the closure flap to the side wall.

- 10 15 4. A paper box for the reception of hats and the like comprising non-rectangular top and bottom portions of like contour, a continuous side wall enclosing the space between the top and bottom portions and permanently connected thereto except for an opening substantially co-extensive in width with that of the box, the continuous side wall having a closure flap projecting from the side wall at one end of the opening, 15 the closure flap deviating from a flat plane to conform to the contour of that portion of the top and bottom portions throughout the length of the opening to fit closely thereagainst and simulate the appearance of the permanent side 20 wall when in closed position, and means for engaging the closure flap to maintain it in closed position.
